elements, the rear frame section may be considered as being "closed," while the front section is "open" in that there are no vertical connecting members, posts, strips or pieces. The "open" front frame section enables loading strips into the machine from the front thereof.

There are two end strip guides for the front frame section, each having a lower rigid post 71 (FIGS. 2 and 2A) and an upper post 73 which is pivotally mounted at 75 to the associated end member of the frame. A latch 77 of conventional design releasably retains each upper pivoted section 73 of the strip guide in its operative position, the top frame member 41 being notched out to accommodate the upper end of each pivoted guide post 73 (FIG. 2B) in order to prevent the leading corner of the topmost strip from jamming into the gap which would exist at the confluence of member 41 and member 37 if the pivoted guide post 73 were not extended above the outwardly bent section 43 of member 41.

When the elevator 13 is lowered and the latches 77 are actuated to release the upper guide sections 73, the guide section can be pivoted downwardly and outwardly to the broken line positions shown in FIG. 1 to enable the stack of strips to be replenished.

The elevator 13 is part of an elevator mechanism which includes a pair of carriages 80 and 81 (FIGS. 2 and 3) the right hand carriage 81 being shown in detail in FIG. 3. It includes a flat body member 83 passing through and guided in vertical slots formed by the guide posts 51 and 53, and having front rollers 85 and rear rollers 87 (FIGS. 2 and 3) engaging said posts. The carriage includes a forwardly located upright portion 89 slotted to receive the vertical flange 91 of the elevator 13.

The carriages 80 and 81 are elevated by the lift cylinder 17 via a sheave and cable mechanism, the cylinder and mechanism being mounted on the rear frame section. The mechanism includes a cable 101 (FIGS. 2 and 6) which is anchored by a turnbuckle 103 to the rear frame section (specifically to the vertical connecting piece 57). The cable extends up and over a sheave 105 (FIGS. 2 and 6) then down and under a sheave 107, up and over a sheave 109, then over a sheave 111, whereafter it extends downwardly and is fixedly connected to the right hand carriage 81. Sheaves 105, 109 and 111 are mounted on the frame 11 (specifically on a sheave mounting plate 113, FIG. 5) while sheave 107 is mounted on a rod eye 115. The rod eye is mounted on the upper end of the piston rod 117 of the lift cylinder 17.

The left hand carriage 80 is similarly elevated by the lift cylinder, there being a cable 131 (FIGS. 2 and 6) anchored at one end by a turnbuckle 133 to the rear frame section, then extending upwardly and over a sheave 135, then downwardly and under a sheave 137, then upwardly and over sheaves 139 and 141, and then fixedly connected to the left hand carriage 80.

By the above arrangement, the lift cylinder 17 which is only about half, or less than half, of the height of the main frame 11, can, by means of the two-to-one mechanical advantage effected by the sheave and cable mechanism, lift the elevator 13 from its lowermost position shown in FIG. 3 (near the base of the frame 11) to an upper position near the top of the frame.

As the strips are elevated and dispensed, the load on the elevator decreases. If the upward force on the elevator were constant, as the strips were dispensed, the decreasing load of the strips would result in an increase in the force pressing the strips against the roller mechanism 15. This could cause jamming of the feeder and/or breaking of the strips.

This problem is avoided in the feeder of the present invention by providing a mechanism to decrease the upward force on the stack of strips as the elevator rises. This mechanism is best shown in FIGS. 3 and 4 and includes an air pressure regulating valve 151 connected in the air leading from the source of air to the pneumatic lift cylinder 17. The regulator 151 is mounted on an angle

bracket 153 which in turn is adjustably mounted, in a manner to be presently described, on the rear frame section.

The pressure regulator has an actuating stem 157 projecting therefrom into engagement with the vertical elongate cam support member 159, which is of angular form as is evident from FIG. 4. The cam support member is pivotally mounted at its lower end on sleeve 171 which pivotally fits on a mounting bolt 173, the latter extending through parallel mounting pieces 174, and secured by a nut 177.

FIG. 4 shows that the angle bracket 153 has a leg 175 which is secured by bolts 176 to the upper mounting piece 174 (as the parts are shown in FIG. 4). The leg has elongate slots so that when the bolts 176 are loosened, the regulator can be shifted back and forth relative to the mounting pieces 174 and thus relative to the pivotal axis of the cam support member 159.

There is a cam strip 181 which is co-extensive with the cam support member 159. The cam strip 181 is supported and held in position by a series of screws, five being shown, and labeled 185, 187, 189, 191 and 193. Screws 185 and 193 are hollow and have screws 184 and 194 slidably extending therethrough and threading into the cam strip 181 so that the heads of screws 184 and 194 abut against the back of screws 185 and 193, respectively, and cause the left hand ends of the latter to abut against the cam strip. Hollow screws 185 and 193 thread through nuts 195 and 197, respectively, which are welded or otherwise secured to the front face of the cam support member. Screws 187, 189 and 191 thread through nuts 199, 201 and 203, respectively, which are welded or otherwise secured to the rear face of the cam support member.

The shaft of carriage roller 87 has an extended portion 211 (FIG. 4) which carries a cam roller 213 disposed in engagement with the front face of the cam strip 181.

OPERATION

As the lift cylinder 17 contracts, the elevator 13 will rise to move the cam roller 213 along the front face of the cam strip 181. It is evident from FIG. 3 that the cam strip is distorted by the screws 185-193 so that the upper portions thereof are progressively disposed further outwardly than the lower portions. Thus, as the carriage 81 rises, the cam support strip will be pivoted counterclockwise slightly, such counterclockwise movement releasing the air regulator stem 157 to progressively decrease the pressure fed to the lift cylinder 17. It is pointed out that the pressure of the air within the regulator 151 acting on the stem 157 applies a biasing force to the cam support strip 159 urging it against the cam roller 213.

FIG. 8 shows the right hand end of the roller assembly 15 and shows the end pairs of the rollers labeled 241 and 242. Disposed beneath the roller assembly is a gate 245 which has shoulder screws 247, 249 and 250 extending through slots 251 provided in the web of the right hand end frame member 37. The gate 245 can be vertically adjusted in any suitable way. The way shown in FIG. 8 comprises an adjustment screw 255 mounted on a bracket 257 in a manner to permit rotation of the screw but to prohibit endwise movement of the screw relative to the bracket. The adjustment screw 255 threads through a lug 259 on the gate member, the lug projecting through a slot 261 provided in the web of the end frame member 37. When a jam nut 263 on the adjustment screw is unthreaded from its jamming position, the position of the upper end of the gate 245 can be adjusted by turning the adjustment screw, whereafter the jam nut can be threaded back to its holding position. The purpose of the adjustment of the gate 245 is to assure that only one strip S is ejected from the strip feeder at a time.

FIGS. 1 and 7 show the means of mounting the dog 21. The dog is carried by a cross head 271 which slidably fits on guides 273 provided on the frame of the machine.

MODIFIED FORM

The present invention can also be incorporated in a subframe 11b to be used as part of a conversion kit. The subframe is shown in FIG. 9 and could be welded to an existing main frame of a feeding machine. What would be done is to remove from the existing machine whatever elevator mechanism is present (except possibly the elevator itself) and then to weld the subframe 11b to the existing main frame 11c.

The subframe would comprise upper and lower members 301 and 303 connected by suitable vertical connecting members including guide posts 51b and 53b. The lift cylinder 17b would be the same as the life cylinder 17 in the first described form of the invention, and the sheave and cable arrangement connecting the lift cylinder to the elevators 80b and 81b would be the same as in the first form of the invention. An elevator 13b of the present invention would be employed. The air pressure regulating system of the first form would be employed so that there would be an air regulator 151b controlled by a cam mechanism, including the cam support member 159b and the cam strip 181b, the cam strip being engaged by a roller 213b carried by the left hand carriage as the parts are shown in FIG. 9. It is further contemplated that the front section of the existing main frame would already be at least partially open, and if not open enough, sufficient elements would be removed to render it open. Vertical guide plates for the wooden strips would be provided preferably with pivoted upper sections of the type shown in FIGS. 1 and 2 of the first form of the invention. After the subframe is welded in place on the existing main frame, and the alterations above mentioned carried out, the resulting strip feeder would have much greater strip capacity than before, and also provide for regulation of the air pressure to the lift cylinder so as to effect a decrease of the lift cylinder pressure as the elevator rises (and the strip load decreases).

An advantage of both forms of the invention is that with the adjustment screws 185-193, the cam strip 181 can be deformed into a non-linear fashion so as to effect the desired decrease in pressure. It is pointed out that the elevator 13 and its carriages and the remaining elevator structure have some weight and frictional resistance to elevation, apart from the weight of the load of the strips. Therefore, simply linearly reducing the upward applied pressure on the stack of strips will not result in the optimum pressure control. A non-linear arrangement can be achieved with the present invention to obtain the optimum results.

Having described the invention in what is considered to be the preferred embodiment thereof, it is desired that it be understood that the invention is not to be limited other than by the provisions of the following claims.

What is claimed is:

1. A strip feeder comprising:

an open rectangular frame which is elongate in a horizontal direction,

an elevator for wooden strips or similar articles of commerce,

means mounting the elevator for movement from a lower position adjacent the bottom of said frame to an upper position adjacent the top of said frame, means for successively ejecting strips from said elevator,

lifting means for automatically raising said elevator as strips are discharged from said elevator,

said lifting means comprising an upright cylinder which is approximately one-half the height of said frame in the telescoped condition of said cylinder,

motion multiplying means connecting said cylinder to said elevator to raise said elevator from its lower to its upper position,

a pair of carriages for said elevator,

spaced guide means guiding said carriages for vertical movement,

said motion multiplying means including reeving means connecting said cylinder to each carriage, control means for decreasing the total applied upward force as the elevator rises,

said control means including a vertical cam strip mounted for pivoting movement, an air regulator for said cylinder disposed in operative relationship to a portion of said strip, and cam engaging means for pivoting said strip and thereby actuating said regulator as said elevator rises.

2. A feeder as in claim 1 wherein said frame comprises a closed rear section and an open front section, the latter providing for replenishing strips to said elevator, and guide means openable to facilitate said replenishing and means to releasably latch said guide means in its closed position.

3. A feeder as in claim 1 wherein there are means for varying the configuration of said cam strip to variously control the upward pressure on said strips.

4. A strip feeder comprising a frame, an elevator for wooden strips or similar articles of commerce, said elevator being mounted in said frame for vertical movement, means for applying an ejecting force successively on said strips, and cylinder means for elevating said elevator as the strips are discharged, a valve for controlling the supply of fluid under pressure to said cylinder means from a source of fluid under pressure, and control means coupled between the elevator and the frame for actuating the valve as the elevator rises so as to decrease the pressure of fluid to said cylinder means.

5. A strip feeder comprising a frame, an elevator for wooden strips or similar articles of commerce, said elevator being mounted in said frame for vertical movement, means for applying an ejecting force successively on said strips, and cylinder means for elevating said elevator as the strips are discharged, control means for varying the upward force of said cylinder means on said elevator as said elevator rises, said control means including a vertical cam strip mounted for pivoting movement,

an air regulator for said cylinder means disposed in operative relationship to a portion of said strip, cam engaging means for pivoting said strip and thereby actuating said regulator as said elevator rises.

6. A feeder comprising a frame, an elevator movably mounted on said frame for supporting a stack of flat objects,

stop means above said elevator, power means for forcing said elevator upwardly to bring the uppermost flat object against said stop means and lifting said elevator in successive stages as said flat objects are dispensed from the top of the stack, and

control means coupled between said elevator and frame and responsive to upward movement of the elevator for regulating the power means so as to maintain substantially constant the contact pressure of said stack against said stop means at all levels of operation of said elevator.

7. A feeder comprising an elevator for supporting a stack of flat objects, stop means above said elevator, power means for forcing said elevator upwardly to bring the uppermost flat object against said stop means and lifting said elevator in successive stages as said flat objects are dispensed from the top of the stack,

- control means responsive to upward movement of the elevator for regulating the power means so as to maintain substantially constant the contact pressure of said stack against said stop means at all levels of operation of said elevator,
- said power means comprising a fluid pressure operated prime mover, said control means acting to decrease the magnitude of the fluid pressure supplied to said prime mover as the elevator rises.
8. In a strip feeder having an elevator, means for elevating said elevator including an air cylinder, an upright strip pivoted at its lower end for movement about a horizontal axis, guide means on said elevator engaging said strip, an air regulator valve having a regulator stem operatively engaging said strip so that as said elevator rises the contour of said strip causes variations in the

position of said regulating stem and hence variations in the force exerted by said cylinder, and means for adjusting the contour of said strip to thereby change the manner in which said stem is actuated.
